(57) **CLAIM**

The ornamental design for a needle arrangement, as shown and described.

DESCRIPTION

FIG. 1 is a bottom, rear, left side perspective view of a needle arrangement;

FIG. 2 is a front view thereof;

FIG. 3 is a rear view thereof;

FIG. 4 is a left side view thereof;

FIG. 5 is a right side view thereof; and,

FIG. 6 is a bottom plan view thereof.

The long dash-short dash lines immediately adjacent the shaded areas represent the bounds of the claimed design. The broken lines shown illustrate portions of the needle arrangement that form no part of the claimed design.
